UNITED STATES PATENT OFFICE.

WILLIAM C. BAKER, OF NEW YORK, N. Y.

IMPROVEMENT IN ELECTRIC STEAM-BOILER ALARMS.

Specification forming part of Letters Patent No. **149,907**, dated April 21, 1874; application filed March 21, 1874.

To all whom it may concern:

Be it known that I, WILLIAM C. BAKER, of the city and State of New York, have invented an Improvement in Boiler-Alarms; and the following is declared to be a specification thereof.

The object of this invention is to furnish an alarm when the water of the boiler is too low, and also to indicate a pressure in excess of a defined amount.

I make use of an expansion-tube to close an electric circuit when the descent of the water in the boiler exposes that tube to the steam heat, and a diaphragm is employed to close the electric circuit if the pressure exceeds a certain fixed point. In either instance the closing of the circuit causes an electro-magnetic alarm to be rung at the engine-room, or in the office connected with the establishment, or in both places, so as to give a warning, and the alarm is so connected that by a circuit-closer operated at the office, or at any distant locality, the proprietor or other person can ascertain whether the apparatus is in working order without sounding the alarm in the engine-room. This apparatus may be employed by boiler-inspectors or others for indicating at a central office or station the condition of all the steam-boilers in a given district.

In the drawing, I have represented the apparatus for giving the alarm in section, and an elevation of the sounding alarms or bells and connections.

The boiler *a* has connecting-tubes *b* and *c* from the steam, and water spaces respectively, and *d* is a tube that is horizontal, or nearly so, and placed at the low-water level, so that the water running from the same, if the water in the boiler becomes too low, exposes the brass expansion-tube *e* to an increased temperature from the steam, and thereby the same is expanded, so that the lever *f* closes the circuit from the battery *g* through *d*, *e*, *f*, *v*, and 2, to the magnetic alarm *h* in the engine-room, and thence the wire 3 passes to the alarm *k* in the office or at the distant station, and the current returns by the wire 4 to the battery, so that both alarms are sounded when the water descends below the established level. If the pressure of the steam

exceeds a predetermined limit, the diaphragm *m* is moved sufficiently to establish a metallic circuit from the battery through *d* and the case *m'* and diaphragm *m*, to the insulated screw *6* and wire *7*, to the magnetic alarms *h* and *k*, so as to sound them as before. If it is desired at the office or distant room to test the condition of the apparatus, the key *r*, or circuit-closing button, is pressed upon, which closes the circuit from the battery through the electro-magnet *s* and alarm *k*. An immediate response of the magnetic alarm *k* indicates that battery and connections are in order, and the electro-magnet *s*, acting upon its armature-lever *t*, link *t'*, and lever *u*, will press the circuit-spring *v* into contact with the lever *f*, and the battery current will divide, a portion going through the magnetic alarm *h*; hence, if the magnet *s* is of greater resistance than the magnet of *h*, there will also be an indication in the engine-room that the circuits are in working order; but if the electro-magnet *s* is of less resistance than that of the alarm *h*, the energy of the magnet of the latter will not be sufficient to sound the alarm, especially when the key or button *r* is only momentarily closed. The expansion low-water indicator may be of any desired character in which the change of temperature expands the metal and closes the circuit.

I am aware that an electro-magnetic alarm has been employed with a pressure-gage, the circuit being closed by the hand; and, also, that a float has been connected with such alarm. These are not always reliable, because the delicate mechanism operating the hand of the pressure-gage is not to be depended upon to close the circuit, and the gage, when located at a distance from the boiler, is still more unreliable, and the float may become obstructed, and it is subject to oscillation. My expansion-tube is reliable, and closes the circuit if the water becomes too low, and the pressure-diaphragm, being located at the boiler, is not liable to being rendered inoperative by sediment or otherwise.

I claim as my invention—

1. The pressure-diaphragm and the low-water expansion-tube, constructed and arranged substantially as specified, in combination with the circuit-closers *f* and *v*, battery

g, and magnetic alarms *h k*, substantially as set forth.

2. The circuit-closing button or key *r*, electro-magnet *s*, levers *t u*, and connections, in combination with the magnetic alarm *k*, low-water and pressure indicators, and connections from a galvanic battery, substantially as and for the purposes set forth.

3. The expansion low-water indicator, in combination with a circuit-closer, electro-magnetic alarm, and battery, substantially as set forth.

4. The pressure-diaphragm *m*, located at or near the boiler, in combination with the insu-

lated adjustable circuit-closer *6* and electro-magnetic alarm, substantially as set forth.

5. An electro-magnetic alarm located at a distance from the boiler, and connected in a metallic circuit from a battery with a circuit-closing low-water expansion indicator at the boiler, and a circuit-closing pressure-indicating diaphragm, substantially as specified.

Dated March 17, A. D. 1874.

W. C. BAKER.
